UNITED STATES PATENT OFFICE

138,773

DESIGN FOR A TIRE REMOVING TOOL

Jay Graves, Berkeley, and Arthur N. Butler, Oakland, Calif., assignors to Speedmaster, Limited, Alameda County, Calif., a copartnership composed of themselves

Application April 3, 1944, Serial No. 113,126

Term of patent 14 years

(Cl. D54—13)

To all whom it may concern:

Be it known that we, Jay Graves and Arthur N. Butler, citizens of the United States and residents, respectively, of Berkeley and Oakland, county of Alameda, State of California, have invented a new, original, and ornamental Design for a Tire Removing Tool, of which the following is a specification, reference being had to the accompanying drawing, forming part thereof.

Figure 1 is a perspective view of the tire re-

moving tool showing our new design, the parts being in position for operation.

Figure 2 is a perspective view of the tool as shown in Figure 1, but with the parts in inoperative rested position.

We claim:

The ornamental design for a tire removing tool, substantially as shown.

JAY GRAVES.

ARTHUR N. BUTLER.
